ULTRA SHORT WAVE AMPLIFIER

Ernst Rahn, Berlin, Germany, assignor to Tele-funkens Gesellschaft für Drahtlose Telegraphie, Berlin, Germany, a corporation of Germany

Application April 19, 1939, Serial No. 268,719
In Germany May 13, 1938

5 Claims. (Cl. 179—171)

The novelty relates to an arrangement for the amplification of ultra short waves by means of triodes. Circuit arrangements are known as such in which a tube with grid connection on two sides and plate connection on two sides is so connected with outer circuits that the grid-anode capacity is compensated by a parallel inductance and that between the cathode and the anode an output circuit is placed, and between the grid and cathode an input circuit. The bringing out, at two sides, of the grid and anode eliminates coupling between the individual circuits. However, it was found that in the case of decimeter waves the known arrangement does not permit of stable conditions of amplification and that disturbances still appear which render the operating safety doubtful.

The novelty of the present invention is based upon an appreciation of the fact that these disturbances, despite all the precautionary measures, are due to a still existing coupling of the individual circuits across the common part of the cathode lead-in, so that no coupling does exist between the input circuit and output circuit and uncontrollable conditions of feed back and counter coupling are present.

In accordance with the present invention the said difficulties are overcome by employing means to render impossible a coupling of the circuits across the common cathode lead. Such means include providing the cathode as well as the other electrodes with connections at two sides, so that the grid-cathode circuit can be placed at the one connection point of the cathode, and the cathode-anode circuit at the other connection point.

Figs. 1 and 2 show two embodiments of the present invention.

The tube structure as shown in Fig. 1 is single-ended (in contradistinction to the push-pull type) and is entirely coaxial. Item K represents the cathode, G is the grid, and A is the anode, whereby respectively towards opposite sides of the tube double electrode connections are provided. The input circuit is designated by E, the output circuit is O, the compensation circuit for the grid-anode capacity is designated by L, shown in this instance connected between that terminal of the grid opposite the input circuit and that terminal of the anode opposite the output circuit.

In place of the bringing out of the cathode on two sides or in addition thereto, it is also possible to provide a tuning of the cathode lead by inserting a tunable circuit such as has already been

come known for various ultra short wave circuits. Such a tuning likewise leads to avoiding the influence of disturbing couplings through the common cathode line.

5 The tuned cathode circuit has no bearing on the heating lines. The latter may, moreover, be choked or may be blocked as regards high frequency by inserting blocking circuits. Preferably, the tuned cathode circuit as well as the blocking circuits for the heating line are designed as tunable coaxial lines. Such an arrangement is shown in Fig. 2 which does not require any further explanation.

What is claimed is:

15 1. An amplifier for ultra short waves comprising an electron discharge device having anode, cathode and grid electrodes enclosed within an envelope, each of said electrodes having terminals extending through opposite sides of said envelope, a source of heating energy for said cathode, and a pair of leads from said source to opposite terminals of said cathode, an input circuit coupled between the grid and cathode terminals on one side of said envelope, and an output circuit coupled between the anode and cathode terminals on the opposite side of said envelope, and means for neutralizing the capacity coupling between input and output circuits resulting from inherent capacity between grid and anode, said means being independent of both said input and output circuits and comprising a reactance coupled between one terminal of said grid and one terminal of said anode.

20 2. An amplifier for ultra short waves comprising an electron discharge device having anode, cathode and grid electrodes enclosed within an envelope, each of said electrodes having terminals extending through opposite sides of said envelope, an input circuit coupled between the grid and cathode terminals on one side of said envelope, and an output circuit coupled between the anode and cathode terminals on the opposite side of said envelope, and means for neutralizing the capacity coupling between input and output circuits resulting from inherent capacity between grid and anode, said means comprising a capacitive connection from one end of said grid to the oppositely located end of said anode.

25 3. An amplifier for ultra short waves comprising an electron discharge device having anode, cathode and grid electrodes enclosed within an envelope, each of said electrodes having terminals extending through opposite sides of said envelope, a source of heating energy for said

cathode, and a pair of connections from said source to opposite terminals of said cathode, said connections constituting paths of high impedance to energy of the operating frequency, an input circuit coupled between the grid and cathode terminals on one side of said envelope, and an output circuit coupled between the anode and cathode terminals on the opposite side of said envelope, and means for neutralizing the capacity coupling between input and output circuits resulting from inherent capacity between grid and anode, said means comprising a capacitive connection extending from that end of the grid which is opposite to the input circuit to that end of the anode which is opposite the output circuit.

4. A high frequency system comprising an electron discharge device having anode, cathode and grid electrodes enclosed within an envelope, each of said electrodes having terminals extending through opposite sides of said envelope, an input circuit coupled between the grid and cathode terminals on one side of said envelope, and an output circuit coupled between the anode and cathode terminals on the opposite side of said envelope, and means for neutralizing the capacity

coupling between input and output circuits resulting from inherent capacity between grid and anode, said means comprising a capacitive connection from one end of said grid to the oppositely located end of said anode.

5. A high frequency single ended circuit comprising an electron discharge device having anode, cathode and grid electrodes enclosed within an envelope, each of said electrodes having terminals extending through opposite sides of said envelope, a source of heating energy for said cathode, and a pair of leads from said source to opposite terminals of said cathode, an input circuit coupled between the grid and cathode terminals on one side of said envelope, and an output circuit coupled between the anode and cathode terminals on the opposite side of said envelope, and means for neutralizing the capacity coupling between input and output circuits resulting from inherent capacity between grid and anode, said means being independent of both said input and output circuits and comprising a resistance coupled between one terminal of said grid and one terminal of said anode.
